COMBINATION LOCK

Henry F. Teichmann, Washington, Pa.

Application November 29, 1933, Serial No. 700,263

10 Claims. (Cl. 70—54)

My invention relates to a combination lock, a lock, that is to say, which may be opened without the aid of a key.

The object of the invention is to provide a combination lock of simplified construction, a lock both economical to manufacture and certain in operation, a lock which is of compact unit construction, adapting it for ready installation in the doors of hotel rooms, and the doors of ordinary homes. In providing a combination lock for such a wide field of service, I have aimed at a structure which in operation is quick to the touch of authorized persons and, yet, a lock which is relatively difficult for unauthorized persons to open. In further accord with the invention, I have provided a combination lock whose combination may, under the control of a master key, be readily and in a moment changed, thereby providing a lock particularly adapted for hotel rooms. That is, the hotel patron may be given the combination to the lock of his room, and may go and come without the bother or need of a key, while from day to day, or when the patron "checks out," the hotel management may change the combination of the lock.

A lock embodying the invention is shown in the accompanying drawings. Fig. I is a view in side elevation of a door equipped with the lock. Fig. II is a fragmentary view, showing in elevation the edge of the door and the visible portions of the lock installed therein. Fig. III is a view in side elevation and to larger scale of the lock unit removed from the door. Fig. IV is a sectional view of the lock unit, taken on the plane IV—IV of Fig. III; the unit is shown in position in the door, and the internal lock elements are omitted. Fig. V is a diagrammatic view of the two groups of push-buttons with which the lock is provided. Fig. VI is a view partly in vertical section and partly in elevation of the lock structure. Fig. VII is a sectional view of the lock, to larger scale, taken on the plane VII—VII of Fig. VI. Fig. VIII is a fragmentary view, showing to larger scale a modification in detail. Fig. IX is a sectional view on the plane IX—IX of Fig. VI, showing to larger scale a detail in construction. Fig. X is a fragmentary view of the front or exposed end of the lock structure, showing the means by which the combination of the lock may be changed. Figs. XI, XII and XIII are sectional views, taken on the plane XI—XI of Fig. VI, and illustrating to larger scale the structure and operation of the lock-controlling push-buttons,

and Fig. XIV is a fragmentary view, showing in section certain details in construction, the line XIV—XIV in Fig. III indicating the plane of section.

The lock comprises a rectangular housing 1 of relatively narrow width. The housing may be pressed in halves of sheet metal, or it may be cast in two parts and assembled over the lock mechanism presently to be described. The housing 1 includes a face plate portion 2 through which the lock bolt 3 extends; in service the lock structure is fitted in an appropriate recess in the door D, and the face plate 2 is inset in the face edge of the door and secured by means of screws 4 in the usual manner (Fig. 15 II). On the inner and outer faces of the door D, overlying the installed lock structure, escutcheons 5 and 6 are secured, and door knobs or handles 7 and 8 are mounted on the operating shaft 9 of the lock, as will be fully described below. 20

The lock structure includes two groups R and S of push-buttons—sixteen buttons in each group. The housing 1 is provided with a shallow recess 10; the push-buttons extend through the wall 1a of the recess, and terminate at their outer ends in substantially common plane with the main wall portion 1b of the housing. As may be seen in Fig. IV, the outer escutcheon 6 of the assembled structure is windowed at 11, which window lies in registry with the recess 10, and is provided with a flap cover 12 that is pivotally secured at 13 to the escutcheon. The flap cover 12 is normally held in closed position (cf. Figs. II and IV), by means of a spring 14, serving to enclose the two groups of push-buttons R, S, and to lend to the structure as a whole a pleasing appearance. 30

In considering the operation of the lock in general, it will be understood that, for the lock bolt 3 to respond to the outside or outer knob 8, 40 a predetermined button in group R must be depressed jointly with a predetermined button in group S. For convenience in designating the lock-operating combination, the buttons in group R are numbered consecutively from 1 to 16, while the buttons in group S bear the characters from A to P (cf. Fig. V). Assuming the combination of the lock to be 1A, the user will raise the flap cover 12, depress simultaneously buttons 1 and A, and, while holding these two buttons depressed, will turn the outer knob 8, to open the door. 50

In the present case, I have employed sixteen push-buttons in each group, and manifestly it is theoretically possible for the lock to be opera- 55

ble in response to any one of two-hundred-and-fifty-six combinations. Of course, the number of groups of buttons, and the number of buttons in each group, may be varied to give five or ten thousand possible combinations, if desired. Upon considering the construction of the lock in greater detail in the ensuing specification, it will be understood that the lock bolt 3 responds to the inner door knob 7, without depressing the 10 push-buttons. An additional general feature will be understood upon considering Fig. II. The flap cover 12 is advantageously adapted to serve as a clip or holder for cards, mail, or papers; that is, the cover 12 may be swung to the dotted line 15 position, and caused, under the influence of spring 14 (Fig. IV), to secure such articles upon the door. Accordingly, the flap cover 12 is of double utility.

Turning now to Fig. VI, the details of my 20 simplified combination lock will be described. The lock bolt 3 is slideable between door-locking and door-releasing positions in a way 15. The bolt 3 is provided with a shoulder 3a, and a compression spring 16 is organized in usual manner 25 to resist inward movement of the bolt and normally to maintain the bolt outward in door-latching position. At its inner end the bolt 3 is slotted, and connected by a pin 17 to the distal end of an arm 18 which is pivotally secured to 30 the housing 1, at 19. Upon a pin 20 a plate 21 is mounted for angular movement; the plate 21 is perforated with holes 22 which are disposed in plan in identical correspondence with the arrangement of the push-buttons in group R; a 35 link 23 interconnects the arm 18 and the plate 21, so that, when the plate swings counterclockwise in the plane of its extent upon the pin 20, the links 23, 18 effect the inward movement of the bolt. A second plate, 24, is mounted upon 40 the pin 20 and is adapted to move in parallelism with the orificed plate 21. The plate 24 embodies a plurality of plungers 25 which is diagrammatically indicated by the shaded circles in Fig. VI. For reasons presently to appear, the plan 45 arrangement of the plungers in plate 24 is in such variance with the arrangement of the push-buttons in group R (and with the similar arrangement of the orifices 22 in plate 21) that of all the plungers carried by plate 24 only one, say, 50 normally lies in alignment with one of the orifices 22 and its associated push-button. In Fig. VI the upper left-hand plunger (25a) in the plate is shown to lie in such registry or alignment with the number 1 push-button of group 55 R (Fig. V). By depressing such number 1 push-button, the plunger 25a is projected into the orifice in plate 21 aligned therewith, whereby the plates 21 and 24 are united for common angular movement about the pin 20.

60 A duplicate or second pair of plates (210 and 240) are pivotally mounted upon a pin 200, and, as in the structure 21, 24 already described, the plate 240 carries a plurality of plungers 250, one of which is adapted to lie in registry with one of 65 the push-buttons of group S and with its associated orifice in plate 210. In this case the plunger 250a lies in registry with the push-button A of group S, so that, by depressing such button A, the plunger 250a is projected into the 70 orifice 220a of plate 210 (cf. Fig. XI for detail), and the plates 210 and 240 are united for joint movement.

The plate 210 is connected by a link 26 to an arm 27, which is secured to a fixed pivot 28; the 75 distal end of arm 27 is connected by a link 29

with the distal end of an arm 30 which is secured to the operating shaft 9 of the lock. A spring 31 is effective normally to hold the arm 27 and its associated links in the illustrated position, the swinging terminal of arm 27 being held in abutment with a stop 32. Means interconnect the two plates 24 and 240, so that the clockwise turning of the outer door knob 8, and in consequence the turning of shaft 9, effects the joint counterclockwise swinging of the two 10 pairs of plates 210, 240 and 21, 24, and manifestly such counterclockwise turning of the plate 21 effects the withdrawal or inward movement of the lock bolt 3 to open the door. The means for so interconnecting the plates 240, 24 comprise a stem 33 which is supported for axial movement in the housing 1. At its right-hand end (Fig. VI), the stem 33 is slidably supported by a bearing 34, while at its left end the shaft is united in a ball-and-socket joint with a shaft 20 35 which is slidably supported in a block 36 rigidly fixed to the housing 1. Each of plates 24, 240 is provided with a yoke 37 embracing a block 38 fixed on stem 33, and each yoke is secured by a pin-and-slot union with its associated block 38. A collar 39 is secured upon shaft 35, and this collar carries a finger 40 which is held to abutment with the block 36 by a compression spring 41. The spring 41 normally holds the finger 40 in engagement with 30 the block 36, whereby the stem 33 is held in such position that (due to the pin-and-yoke connections 37, 38) the plates 24, 240 each lie in predetermined relation to its complementary orificed plate (21, 210). Accordingly, the critical push-buttons (in this case the push-buttons 1 and A) are properly aligned with the plungers 25a, 250a, so that, by depressing such two push-buttons, the plates 21, 24 and 210, 240 become 35 united for joint angular movement. When these 40 said plates are so united, the clockwise rotation of the shaft 9 (effected by turning the outer door knob 8) manifestly produces the joint counterclockwise swinging of the plates 210, 240, which swinging effects the right-to-left shifting 45 of the stem 33 against the resistance of spring 41 and an accompanying counterclockwise turning of the plates 21, 24. Thus, by means of linkage 23, 18, the lock bolt 3 is withdrawn against the resistance of spring 16, and the door in 50 which the lock is installed may be opened. Upon release of the door knob, the springs 16, 31 and 41 restore the parts to their initial positions illustrated in Fig. VI.

In its simpler form the lock may be constructed as described above, no provision being made for changing the combination of buttons, to admit of operation of the lock. However, I contemplate that in hotels in particular it may be desirable often to change the lock's combination, 55 and, to this end, I provide a dial head 42 in a chamber 43 within the frontal plate 2 of the housing 1. The dial head 42 is secured to the one terminal of a pin 44 which extends with sliding fit into the shaft 35; the pin 44 is equipped with a key 45 lying in an elongate slot 46 formed in the shaft 35; and the engagement between the pin 44 and shaft 35 is obviously such that the shaft may move axially when the stem 33 shifts during lock operation. In my 60 changeable combination lock the abutment between the finger 40 and the block 36 is of an adjustable nature. That is to say, the block 36 is provided with a plurality of radially arranged slots 47; as may be observed in Fig. VI, these 65 70 75

slots are graduated in depth, and the finger 40 is adapted to nest in one of the slots, and at its end abuts the bottom or end wall of the slot. By placing the finger 40 in one or another of the slots 47 which, as has been already indicated, are of graduated depth, the initial or dormant positions of the shaft 35 and stem 33 may be regulated. Accordingly, the initial or dormant positions of the plates 24, 240 may be varied with respect to the orificed plates 21, 210 respectively, and one or another of each set of plungers 25, 250 may be brought into registry with one or another of the push-buttons in each group R, S respectively, and with the corresponding orifices 22, 220 of each of the plates 21, 210 which lie in alignment with the particular push-buttons. Thus, in adjusting the collar 39 angularly, and in selectively positioning the finger 40 in one or another of the slots 47, the push-button of each group which is effective in lock operation may be changed, so altering the combination of the lock.

To accomplish such altering of the combination, the dial head 42 is withdrawn from the chamber 43. The key 45, engaging the left end of slot 46, carries the shaft 35 with the pin 44 to the left, as the dial head is withdrawn, and so the finger 40 is moved clear of the slotted block 36. Next, the dial head is rotated, to move the finger 40 into alignment with any other of the slots 47, and then the dial head is thrust back into the chamber 43, the spring 41 forcing the shaft 35 to the right and causing the finger 40 to seat in the selected slot 47. As indicated in Fig. X, the dial head may be provided with a key socket 48, so that a specialized key is required to permit the combination-changing manipulation. Additionally, the wall of the chamber 43 may comprise a numbered dial (Fig. X) and the dial head may include an index, to assist the attendant changing the combination, and in ascertaining, by a predetermined correlation between the dial numbers (1-12 in this case), what the combination of the lock is at any time. Advantageously, a cover plate 49 is embodied in the frontal plate 2 of the lock, and is slidable in a way 50 (Figs. II and VI). Normally, the cover plate overlies or closes the chamber 43, and at will may be slid downward, to give access to the dial head 42.

If desired, and in many cases it will be desired, a further refinement may be embodied in the lock. The cover plate 49 may be made subject to the action of an arm 51 located within the lock. The arm 51 is connected pivotally at one end to a lug 52 which is integrated with the plate and projected through a slot 53 in the frontal wall of housing 1. The opposite end of arm 51 is joined, by a slot-and-pin connection, with the distal end of a lever 54 adapted to swing upon a fixed axis 55. A key-hole 56 and a key-socket 57 are provided for the reception of a master key, and any convenient means may be included in the key-socket, to prevent rotation of all but the properly designed and intended key from turning effectively. As a simplified example, the key-socket may comprise a flange 58 which is notched along its edge, requiring that the key be correspondingly notched or grooved, to permit its counterclockwise rotation. The lever 54 includes an end portion 54a, and, upon turning the proper key counterclockwise in the key-socket 57, the lever portion 54a is engaged by the blade of the key, and the lever 54 is swung clockwise. In consequence, the arm 51 is swung and drawn

downward, effecting the movement of the cover plate 49 away from the entrance to chamber 43. Advantageously, the lock bolt 3 may be equipped with a laterally projecting pin 59, so that the master key may also be effective to withdraw the lock bolt and open the door in which the lock is installed. Manifestly, when the lever 54 is swung clockwise under the action of the master key, it engages the pin 59 and moves the lock bolt 3 to the right—into door-releasing position.

Fig. VIII illustrates a modification in the means for connecting the plates 24, 240 to the stem 33, to the end that minute adjustment of such plates may be made with respect to the plates 21, 210. Each of plates 24, 240 includes a rigid lug or arm 60, and the yoke 61 embracing the block 38 on the stem is secured to the arm 60 by means of an opposed pair of adjustable screws 62, 62. As in the structure already described, the yoke is united to the block 38 by means of a pin-and-slot connection (63), and clearly the screws 62, 62 admit of minute angular adjustments of the plates 24, 240 with respect to the plates 21, 210 in their normal or dormant positions, such adjustments being sometimes desirable, to establish exact correlation of the parts.

Turning now to a detailed consideration of the push-button structure and operation, attention is directed to Fig. XI. Each push-button comprises a sleeve 64 which extends through the wall 1a of the housing 1; the sleeve 64 is provided with a flange 65, to limit outward movement through wall 1a, and a cap 66 is secured (by spot-welding, or by threaded union) to the outer tip of the sleeve; and the peripheral edge 66a of the cap affords a stop for limiting inward movement of the sleeve when the button structure is depressed by the user. A pin 67 extends with sliding fit into the bore of sleeve 64, and the pin includes a flat, circular head 68, between which head and the flange 65 on the sleeve 64a compression spring 69 is effective.

The push-button shown in Fig. XI is the push-button of group S, bearing the character A, and, as has been already mentioned, in this case the push-button A is the only push-button of group S which is aligned with a plunger in the plate 240. Accordingly, the depression of such push-button is adapted to effect union of the plates 210, 240 for lock operation. As Fig. XI indicates, the plungers 250 each comprises a shank to which the reference character 250a is immediately applied. A flat circular head 71 is provided at one end of the shank, and a tip member 72 at the opposite end. The head 71 is coextensive in plan with the head 68 on the push-button pin 67, and the tip member 72 is of greater diameter than the stem 250a, providing a shoulder which normally engages an abutment 73 in the plate 240. A compression spring 74 is mounted upon the stem 250a in a recess 70 in the plate 240; the spring 74 at one end bears against the wall of the recess and at the other end against the head 71 of the stem; this spring 74 is effective normally to maintain the tip member 72 against the abutment 73, and the proportions of the parts are such that the outer face of the stem head 71 lies flush with, or in common plane with, the free face (the right-hand face, Fig. XI) of the plate 240, while the tip member 72 lies within the inner or left-hand face of such plate. Under such circumstances the plate 240 may swing independently of the plate 210 in response to the turning of the door knob, and the lock

bolt 3 can not be withdrawn. When, however, the push-button A is depressed, the spring 69 dominates the spring 74, and forces the plunger stem 250a to the left, whereby the tip member 72 extends into the orifice 220a in the plate 210. Thus, so long as the push-button A is depressed, the two plates 210, 240 are interlocked for joint movement. By conjointly depressing the appropriate button in group R, the plates 21, 24 are similarly united, and the lock structure becomes responsive to the door knob 8, as explained above.

Fig. XII illustrates the position of the parts when the push-button A is depressed, and shows how the plunger tip member 72 affords an interlocking of the plates 210, 240 for joint angular movement upon the pin 200 (Fig. VI). In this case, all the push-buttons in group S, save the push-button A, are out of registry with their associated plungers 250, and Fig. XIII shows, for example, the push-button B. It will be observed that the head 68 of this push-button engages in part the head of the plunger 250 and in part the face of the plate 240, whereby, while the push-button B may be depressed against the resistance of spring 69, its plunger 250 remains stationary, affording no interlocking of the plates 210, 240. So it is with all the push-buttons in groups R and S, excepting the two lock combination buttons 1 and A.

It will be understood that the structure of the push-buttons collectively is such that the plate 240 (and 24) may be shifted angularly in the plane of its expanse. As stated, the outer face 35 of head 71 of each plunger 250 lies normally in common plane with the free or right-hand face (Figs. XI-XIII) of the plate 240, so that, as the plate moves, the heads 68 of the push-buttons "ride" the plane surface provided by the face of 40 the plate, together with the outer faces of the plunger heads 71 embodied in the plate. Thus, the push-button structures admit of the swinging of the plates 21, 24 and 210, 240 during lock operation, and permit of the adjustment of the 45 plates 24, 240, to change the combination of the lock in the manner already described. It may be remarked that the dimensions of the recesses 70 in the plates 24, 240 are such that, when the combination push-buttons are depressed (in this case the buttons 1 and A), there is sufficient clearance between the side walls of the recesses 50 and the edges of the heads 68 located therein (Fig. XII), to permit adequate lock-operating swinging of the plates.

It is common in lock construction to have the inner door knob (the knob 7 in this case) adapted to open the lock without need of a key or other lock-opening means. In accordance with 60 such common practice, I mount the door knob 7 idly upon the lock shaft 9 (Figs. VI and XIV), and connect an arm 180 to the knob, by any suitable means such as a sleeve 181. Thus, by turning the inner door knob 7, the arm 180 engages 65 the pin 17 in the lock bolt 3, and withdraws the bolt independently of the combination lock mechanism.

I claim as my invention:

1. In a lock structure, the combination of a 70 lock bolt, means for shifting said bolt from locking to releasing position, a handle, operating mechanism connected to said handle, a plurality of movable buttons, and means responsive to the movement of at least one of said buttons for uniting said mechanism with said bolt-shifting

means, whereby said bolt becomes responsive to the movement of said handle.

2. In a lock structure, the combination of a lock bolt, means connected to said bolt and in response to whose movement said bolt moves, mechanism for moving said means, which mechanism is normally movable independently of said means, a plurality of movable buttons, means responsive to the movement of several of said buttons for temporarily uniting said first-mentioned 10 means and said mechanism.

3. In a lock structure, the combination of a lock bolt and a handle, mechanism for moving said bolt including a swingable member, means normally disengaged operatively from said member and movable in response to the movement of said handle, and a plurality of button structures, in response to the shifting of a predetermined combination of which button structures said member and said means are interengaged for 20 lock operation.

4. In a lock structure, the combination of a lock bolt and a handle, mechanism for moving said bolt including a plurality of swingable members, means normally disengaged operatively from said members, and a plurality of button structures, in response to the shifting of a predetermined combination of which button structures said swingable members are rendered effective with said mechanism and said means 30 for lock operation.

5. In a lock structure, the combination of a lock bolt and a handle, mechanism including two pairs of members, the one member of each pair being normally disengaged from its companion member, and a plurality of buttons, means movable in response to the shifting of a predetermined combination of said buttons for temporarily interengaging the members of each of said pairs, and means connected to said 40 handle and adapted upon said interengagement of said members to move said bolt in response to movement of said handle.

6. A combination lock including two members adapted to be united for lock operation, means 45 for uniting said members, which means comprise a movable button, a spring for holding said button in a normal position, a spring-backed plunger adapted for registry with said button, said plunger being movable in response to the 50 movement of said button from normal position and adapted to unite said two members for joint movement.

7. A combination lock including two members adapted to be united for lock operation, means 55 for uniting said members including a spring-backed button and a spring-backed plunger, said plunger being normally adjustable laterally of said button, and, when aligned therewith, said plunger yielding to the depression of said button 60 to effect the uniting of said members.

8. A combination lock including two members adapted to be united for lock operation, one of said members including a group of plungers spaced-apart in the plane of its expanse and 65 movable transversely thereof, a group of buttons, at least one of said buttons being adapted for registry with one of said plungers, whereby, upon manipulation of such button, said plunger responds to effect union of said two members, 70 said member including said group of plungers being normally adjustable relatively to said group of buttons for changing the button and plunger in registry.

9. A lock structure comprising a lock bolt, 75

means for shifting said bolt from locking to releasing position, a handle, operating mechanism connected to said handle, a plurality of movable buttons, means responsive to the movement of 5 at least one of said buttons for uniting said mechanism with said bolt-shifting means when said last-mentioned means are in idle or normal position, whereby the bolt becomes responsive to the movement of said handle, an adjustable 10 element movable with the united bolt-shifting means and operating mechanism, the adjustment of said element determining the idle or normal position of said bolt-shifting means, and means for adjusting said element for altering 15 the idle or normal position of said bolt-shifting means, and thereby changing the but-

ton which is instrumental in uniting the bolt-shifting means with said mechanism.

10. In a lock structure, a lock bolt, means for shifting said bolt, a movable member normally disengaged from said bolt-shifting means, a handle, connections from said handle to said movable member, adjustable means for determining the idle position of said movable member relatively to said bolt-shifting means, and a group of push-buttons, the selective depressing of which push-buttons is adapted to unite said movable member with said bolt-shifting means, and the proper selection of push-buttons being dependent upon the adjusted idle position of said movable member.

HENRY F. TEICHMANN.
